UNITED STATES PATENT OFFICE

JOHN REICH, OF PHILADELPHIA, PENNSYLVANIA.

IMPROVEMENT IN SOFA-BEDSTEADS.

Specification forming part of Letters Patent No. 177,958, dated May 30, 1876; application filed April 13, 1876.

To all whom it may concern:

Be it known that I, JOHN REICH, of the city and county of Philadelphia, and State of Pennsylvania, have invented a new and useful Improvement in Sofa-Bedsteads; and I do hereby declare the following to be a clear and exact description of the nature thereof, sufficient to enable others skilled in the art to which my invention appertains to fully understand, make, and use the same, reference being had to the accompanying drawings, making part of this specification, in which—

Figure 1 is a side view of the sofa-bedstead embodying my invention. Fig. 2 is a rear view, partly broken away. Fig. 3 is a horizontal section of a portion in line $\alpha\alpha$, Fig. 2.

Similar letters of reference indicate corresponding parts in the several figures.

My invention consists of a sofa having a hinged back and hinged side pieces or arm-rests, in combination with fastenings for holding the parts either folded and open, relatively to the needs of the sofa, or the bedstead into which the sofa may be converted.

Referring to the drawings, A represents the frame of the sofa, and B the back hinged thereto. C represents the arm-rests, each of which consists of two parts, C' C'', hinged together, and one of the parts C' is secured to the frame A, the hinged part C'' being adapted to be opened out to form an extension or continuation of the fixed part C'. To the parts C'', at the end to which they are attached to the parts C', there are secured spring-catches D, which project rearward, and are adapted to engage with a rod, E, secured to the front face of the back B, at such points that when the back is in its normal position or upright, the catches D engage with the rods, and hold the back against the arm-rests, there being presented the appearance and advantages of a sofa. To the back there are pivoted hooks F, which are so located that their ends may be brought in contact with the catches D, so as to hold the latter firmly against the rod E, and thus prevent rearward or opening motion of the back.

The catches D will be so located that when the hinged parts C'' are opened or extended, and the hooks are properly rotated, the hooks

will rise on the outside of the hinged parts or engage with said parts, and thus prevent closing or folding motions of said hinged parts, as will be hereafter stated.

The hooks will receive rotary motions by means of crank-rods a a, the upper ones of which are connected to rotary buttons b, which are swiveled to the back B, and, besides serving to operate the crank-rods a and hooks F, they also act as guards for the rear of a sofa.

Within the lower portion of the frame A will be fitted a receptacle, G, for bed-clothing, &c., and which, when the sofa is converted into a bed, will support the back when lowered, as shown by the dotted lines, Fig. 1.

The operation is as follows: When the sofa is to be converted into a bed, the buttons b will be rotated, whereby the hooks F will be moved clear of the catches D. Then by pressing the back rearward, the springs of the catches will be overcome, and the heads of the catches will disengage themselves from the rods E. The back is thus disconnected from the arm-rests, and it may be swung downward to full extent, so as to form a horizontal continuation of the seat of the sofa. Now, move around the hinged pieces C'' of the arm-rests so that they extend over the lowered back B, and rotate the buttons b, so that the hooks F rise on the outside of the hinged pieces C'', or engage therewith, whereby the latter are prevented from closing or folding against the fixed pieces C' of the arm-rests. It will be seen that the sofa is converted into a convenient and serviceable sofa-bed.

To restore the parts to their normal position, or reproduce the sofa, turn the buttons so as to move down the hooks F. Fold the arm-rests, raise the back, and force it against the arm-rests, so that the catches D engage with the rods E. Rotate the button, so that the hooks F press against the catches, and, the latter being locked, the back cannot disengage from the arm-rests.

Having thus described my invention, what I claim as new, and desire to secure by Letters Patent, is—

1. The hinged back B and arm-rests C, connected by catches D, in combination with the locking-hooks F, substantially as and for the purpose set forth.

2. The rotating guard-buttons b and rotating hooks F, in combination with the fastening-catches D of the arm-rests, and hinged

back, substantially as and for the purpose set forth.

JOHN REICH.
